TELEVISION SCANNING DEVICE

James Michael Robinson, Evansville, Ind., assignor of one-fourth to Thomas Andrew Gosman, Dubois County, Ind.

Application September 10, 1932
Serial No. 632,603

8 Claims. (Cl. 178—6)

This invention relates to a television device and has for an object to provide an improved scanning apparatus for use in television devices, it being an object of this invention to provide a scanning apparatus which may be used for either transmitting or for receiving transmitted television images.

A further object of this invention is to provide an improved scanning apparatus for television devices comprising two overlapping intersecting scanning disks, each scanning disk being provided with a plurality of slots therethrough.

A further object of this invention is to provide a scanning disk having a plurality of apertures therethrough and to provide behind each aperture a movable scanning plate having an angular slot, which angular slot will be held in a predetermined position as it moves across a frame and is overlapped by an intersecting angular slot on a companion rotatable scanning disk.

A further object of this invention is to provide means for holding the scanning slot of a movable scanning plate on a rotatable scanning disk at a predetermined angle as the scanning slot is intersected by an angular slot on an overlapping companion scanning disk.

Yet an additional object of this invention is to provide a means for holding the scanning slot and a movable plate on a scanning disk at a predetermined angle, which means will be operated automatically by the rotation means of the two scanning disks, so that the scanning plate will always move in proper synchronism with both scanning disks without the necessity of further attention.

With the foregoing and other objects in view, as will hereinafter become apparent, this invention comprises the constructions, combinations and arrangements of parts hereinafter set forth, disclosed and shown on the accompanying drawing. In this drawing,

Figure 1 is a front elevation of the invention showing the scanning disks, said disks being partly broken away,

Figure 2 is a rear view of same showing gearing for operating scanning disks, and

Figure 3 is a sectional view taken on line 3—3 of Figure 2, also showing neon lamp or any other suitable lamp and viewing lens.

The scanning apparatus 10 constituting this invention may be used either with the television apparatus for transmitting images or with the television apparatus for reproducing images. As clearly shown in Figure 3, a television apparatus

for reproducing pictures is schematically shown, a neon tube 12 receiving transmitted electrical impulses reproduces the electrical impulses into light impulses which pass through the frame, schematically shown at 11, and the scanning apparatus 10 to a protecting lens schematically shown at 13. The scanning apparatus 10 consists of two rotatable disks 14 and 15, the rotatable disks 14 and 15 being each rotated from a common power shaft 16 to a suitable gearing mechanism or train 17, the gear mechanism being so selected that the disk 14 will make a desired predetermined number of revolutions for each revolution of the disk 15.

The gear mechanism or train 17 consists of a drive gear 18 driven by a screw pinion 19 on power shaft 16. A large pinion 20 integral with the gear 18 operates through gear 21, 22 and 23 to rotate the pinion 24 on the shaft 25 on which the disk 14 is mounted. A small pinion 26, likewise integral with the drive gear 18, meshes with the gear 27 on a hollow shaft 28 on which the disk 15 is mounted. The disk 14 is provided with a plurality of angular circumferentially spaced slots 30, which pass successively across the frame 11 as the disk 14 is rotated. The disk 15 is provided with a plurality of apertures 31, which likewise pass successively across the frame 11.

As will be obvious from the gearing mechanism 17, as shown in Figure 2, the disks 14 and 15 rotate in opposite directions, the disk 14 rotating much faster than than the disk 15.

A scanning plate 32 provided with a scanning slot 33 is pivotally mounted as at 34 behind each aperture 31. As the disk 15 is rotated, the scanning plate 32 is so pivoted on its pivot 34 that its scanning slot 33 will move across the frame 11 in a substantially straight path, that is, the plate 32 will be pivoted about its pivot 34 an amount just sufficient to compensate for the rotation of the pivot 34 about the center of the disk 15. Each scanning plate 32 has its other end formed into a boss or projection 35 which is pivotally mounted at 36 on a bell crank 37. A spring 38 secured at 39 to the disk 15 presses against the boss or projection 35 and tends to hold or to return the scanning plate 32 to its non-moving position.

The bell crank 37 is pivotally connected by a link 40 to a slide arm 41 which passes through a slide guide 42. The free end of the slide arm 41 presses against the circular plate 43 mounted on the stationary shaft 44 through the hollow shaft 28. Projecting from one side of the circu-

lar plate 43 is a cam 45 in the path of the free end of the slide arm 41, the cam 45 being substantially in alignment with the frame 11, causing the scanning plate 32 to pivot as it passes the frame 11 to hold the scanning slot 33 at substantially the same angle as it crosses the frame 11. As soon as the scanning slot 33 has passed beyond the end of the frame 11, the slide arm 41 will have passed beyond the end of cam 45, allowing the spring 38 to return the scanning plate 32 to the normal position.

In operation, the two scanning disks 14 and 15 will be rotated in the predetermined ratio to each other by means of the power shaft 16, and as each scanning plate 32 behind its aperture 31 passes across the frame 11, it will be tilted by means of the cam mechanism just described to hold the scanning slot 33 in substantially the same angle across the frame 11. Meantime, the angular slot 11 will intersect across the angular slot 32, allowing a beam of light from the tube 12 to pass through the intersected slot in a plurality of substantially parallel paths, it being intended that the disks 14 and 15 will rotate at such a ratio to each other that one angular slot 30 will pass across the frame 11, while the angular slot 33 moves only its own width across the frame 11, thus causing the scanning rays to travel in a plurality of substantially horizontal parallel paths.

The novel features and the operation of this device will be apparent from the foregoing description. While the device has been shown and the structure described in detail, it is obvious that this is not to be considered limited to the exact form disclosed, and that changes may be made therein within the scope of what is claimed without departing from the spirit of the invention.

Having thus set forth and disclosed the nature of this invention, what is claimed is:

1. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, and a pivoted scanning plate mounted on said apertured scanning disk behind each aperture, each scanning plate having a slot therein.

2. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, and a pivoted scanning plate mounted on said apertured scanning disk behind each aperture, each scanning plate having a slot therein, said scanning disks being mounted in overlapping relation whereby said angular slots and said apertures will intersect each other.

3. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, a pivoted scanning plate mounted on said apertured scanning disk behind each aperture, each scanning plate having a slot therein, said scanning disks being mounted in overlapping relation whereby said angular slots and said apertures will intersect each other, and

means for rotating each of said scanning disks in predetermined ratio to each other from a common power source.

4. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, a pivoted scanning plate mounted on said apertured scanning disk behind each aperture, each scanning plate having a slot therein, said scanning disks being mounted in overlapping relation whereby said angular slots and said apertures will intersect each other, means for rotating each of said scanning disks in predetermined ratio to each other from a common power source, and means for pivoting each scanning plate on said apertured disk as it is intersected by the angular slots on said other scanning disk to maintain the slot in said scanning plate at a substantially constant angle.

5. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, a pivoted scanning plate mounted on said apertured scanning disk behind each aperture, each scanning plate having a slot therein, said scanning disks being mounted in overlapping relation whereby said angular slots and said apertures will intersect each other, means for rotating each of said scanning disks in predetermined ratio to each other from a common power source, and means for pivoting each scanning plate on said apertured disk as it is intersected by the angular slots on said other scanning disk to maintain the slot in said scanning plate at a substantially constant angle.

6. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, a pivoted scanning plate mounted on said apertured scanning disk behind each aperture, each scanning plate having a slot therein, said scanning disks being mounted in overlapping relation whereby said angular slots and said apertures will intersect each other,

means for rotating each of said scanning disks in predetermined ratio to each other from a common power source, means for pivoting each scanning plate on said apertured disk as it is intersected by the angular slots on said other scanning disk to maintain the slot in said scanning plate at a substantially constant angle, said means comprising an arm pivoted to the free end of each scanning plate, a stationary cam actuating said arm as the disk rotates, and a spring means restoring said scanning plate to normal position after said stationary cam has been passed.

7. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout,

spaced thereabout, a pivoted scanning plate mounted on said apertured scanning disk behind each aperture, each scanning plate having a slot therein, said scanning disks being mounted in overlapping relation whereby said angular slots and said apertures will intersect each other, means for rotating each of said scanning disks in predetermined ratio to each other from a common source, means for pivoting each scanning plate on said apertured disk as it is intersected by the angular slots on said other scanning disk to maintain the slot in said scanning plate at a substantially constant angle, said means comprising a bell crank arm pivoted to the free end of each scanning plate, a slide arm pivoted to said bell crank arm, a guide for said slide arm mounted on said apertured plate, the other end of said guide arm being free, and a stationary cam in the path of said free end of said slide arm, whereby said stationary cam will actuate said slide arm and pivot the scanning plate as it passes the path of intersection with the angular slot on said other scanning disk.

8. In a television apparatus, a scanning device comprising in combination a pair of scanning disks, one of said scanning disks having a plurality of angular slots circumferentially spaced thereabout, the other of said scanning disks having a plurality of apertures circumferentially spaced thereabout, a pivoted scanning plate mounted on said apertured scanning disk behind each aperture, each scanning plate having a slot therein, said scanning disks being mounted in overlapping relation whereby said angular slots and said apertures will intersect each other, means for rotating each of said scanning disks in predetermined ratio to each other from a common source, means for pivoting each scanning plate on said apertured disk as it is intersected by the angular slots on said other scanning disk to maintain the slot in said scanning plate at a substantially constant angle, said means comprising a bell crank arm pivoted to the free end of each scanning plate, a slide arm pivoted to said bell crank arm, a guide for said slide arm mounted on said apertured plate, the other end of said guide arm being free, a stationary cam in the path of said free end of said slide arm, whereby said stationary cam will actuate said slide arm and pivot the scanning plate as it passes the path of intersection with the angular slot on said other scanning disk, a yieldable spring mounted on said apertured disk adjacent each scanning plate, said yieldable spring permitting said scanning plate to pivot as its slide arm is actuated by said stationary cam, and restoring said scanning plate to the non-pivoted position after said stationary cam has been passed.

10 15 20 25 30 35 40 45 50 55 60 65 70 75 80 85 90 95 100 105 110 115 120 125 130 135 140 145 150

means for rotating each of said scanning disks in predetermined ratio to each other from a common source, means for pivoting each scanning plate on said apertured disk as it is intersected by the angular slots on said other scanning disk to maintain the slot in said scanning plate at a substantially constant angle, said means comprising a bell crank arm pivoted to the free end of each scanning plate, a slide arm pivoted to said bell crank arm, a guide for said slide arm mounted on said apertured plate, the other end of said guide arm being free, a stationary cam in the path of said free end of said slide arm, whereby said stationary cam will actuate said slide arm and pivot the scanning plate as it passes the path of intersection with the angular slot on said other scanning disk, a yieldable spring mounted on said apertured disk adjacent each scanning plate, said yieldable spring permitting said scanning plate to pivot as its slide arm is actuated by said stationary cam, and restoring said scanning plate to the non-pivoted position after said stationary cam has been passed.

JAMES MICHAEL ROBINSON. 105
